UNITED STATES PATENT OFFICE.

HARRY S. STRONACH, OF TACOMA, WASHINGTON.

BORING-MACHINE.

1,311,626.

Specification of Letters Patent. Patented July 29, 1919.

Application filed March 18, 1918. Serial No. 223,207.

To all whom it may concern:

Be it known that I, HARRY S. STRONACH, a citizen of the United States, residing at Tacoma, in the county of Pierce and State of Washington, have invented certain new and useful Improvements in Boring-Machines, of which the following is a specification.

The present invention relates to boring machines and more particularly to wood boring machines for boring out pedestals, balusters, posts and the like.

It is the object of the invention to provide a boring machine which combines speed of operation and accuracy.

To this end, the invention comprises a hollow shaft having a thread of very wide pitch on the outside and a shiftable support for accurately holding the shaft on a fixed axis.

A more particular object is the provision of mechanism for accurately supporting and guiding a threaded barrel adapted to bore holes of different diameter in a single operation.

The invention will be more fully described in the annexed specification and more particularly defined in the claims.

In the drawing,

Figure 1 is a side elevation of a machine embodying the invention;

Fig. 2 is a fragmentary view of the shaft showing the thread on the surface thereof;

Figs. 3 and 4 are sectional views on lines 3-3 and 4-4 respectively;

Figs. 5 and 6 are a plan view and end view of the support for the shaft, and

Figs. 7 and 8 are a cross-sectional view, and side view of a detail.

Having reference to Fig. 1, 10 represents a suitable frame having the usual guide rails 11 on which is mounted the operating mechanism of the machine. The operating mechanism comprises a pulley 12 mounted on uprights 14 of a frame 16. 17 is a carriage movable along the guide rails 11 and carrying the column or stock to be bored. The hollow shaft which comprises a front portion 18 for boring a hole of relatively small diameter and a rear portion 19 for boring a hole of larger diameter is secured to the pulley 12.

Supports 20 and 21 engage the shaft intermediate its ends to hold it in a fixed axial line. The shaft is provided on its outer surface with a thread, preferably a

double thread of large pitch which extends over the shaft substantially the full length thereof. The height of the thread on the front portion 18 is proportional to the diameter of the hole to be bored thereby and the height of the thread on the portion 19 is proportional to the diameter of the larger hole.

The front end of the barrel is provided with the usual cutting lips (not shown) and a reamer is secured to the shaft to enlarge the bore made by the former.

Fig. 2 shows the point of the shaft where the reamer is attached. The double thread 26 which from the front end of the shaft to the reamer has, as has been stated, a height proportional to the size of the bore made by the auger, is continued toward the rear end of the shaft, but its height is increased in proportion to the counter bore to be made by the reamer.

The reamer knives 27 and 28 (Fig. 6) are preferably inserted in channels 29 in the crest portion of the enlarged thread 31, and secured therein by a wedge element 32 forced against the body of the reamer by means of a screw 33 or in any other suitable way.

At the point where the height of the thread is increased, an off-set 34 is made in the double thread for a purpose to be subsequently described. The reamer is so disposed that its cutting edge 30 projects into the off-set 34.

The supports 20 and 21 have at their upper ends angular seats 35 in which is fitted a stationary box 36 composed for convenience of two halves 36' and 36''. This stationary box has a cylindrical opening which forms a bearing for the cylindrical box 37. The cylindrical box 37 (Figs. 7 and 8) has internal ribs 38 and 39 to engage in the grooves of the thread and bear with their inner faces 40 upon the bottom of the thread. These ribs are of such height that the space between them can accommodate the reamer and provides a clearance 41. When the box 37 is exactly over the reamer knives, the ribs 38 and 39 clear the knives 27 and 28 as indicated in Fig. 6. The stationary box 36 has flanges 42 and the cylindrical box 37 has flanges 43 to prevent relative lengthwise movement.

To facilitate the taking apart of the various elements, the supports 20 and 21 have re-

movable head plates 44. This plate may be attached by means of stud bolts 45 and nuts 46 or in any other desired manner.

The supports or pedestals 20 and 21 are constructed to have sliding movement along rails 11 and suitable means may be provided whereby they are moved toward the rear end of the shaft as the column or stock to be bored is advanced. I do not limit myself to any particular arrangement in that respect, since motion may be imparted to the supports in various ways and by various means, independently or independently of each other.

The operation of the device is as follows: The shaft is rotated by the pulley 12 and the carriage 17 is advanced. As the carriage moves along guide rails 11, the supports 20 and 21 are gradually moved to the right. During such motion the cylindrical box 37 revolves with the shaft and the ribs 38 and 39 slide along the grooves of the thread. Since the thread is continuous, the cylindrical box can pass from the thread of the front portion 18 over the thread of the rear portion 19 and since the cutting edge projects into the offset 34, which is within the confines of the thread, the box 37 can pass over the reamer. The supports may therefore pass over the full length of the shaft as if the shaft were of uniform diameter. The ribs 38 and 39 engage the bottom of the thread and thereby hold the shaft in a fixed axial line.

The thread 19 carries the saw dust rearwardly and thereby clears the reamer blades. The thread 18 performs a similar function. However, a conveyer screw or worm 47 may work within the shaft to more rapidly remove the saw dust and shavings from the bore and clear the auger. This conveyer screw 47 may be driven by a pulley 13 mounted on uprights 15 of the frame 16 or other suitable means. Constructions of this kind are well known and do not form a part of my invention.

I claim:

1. In a boring machine, the combination of a shaft having threads on its outer surface and a support for holding the shaft on a fixed axial line, said support having means to bear on the bottom of the thread.

2. In a boring machine, the combination of a shaft having threads on its outer surface and a shiftable support for holding the shaft on a fixed axial line, said support having means to bear on the bottom of the thread.

3. In a boring machine, the combination of a shaft having its outer face threaded and adapted to bore holes of different diameters and a support for holding the shaft on a fixed axial line, said support having means to bear on the bottom of the thread and being shiftable along the shaft substantially the full length thereof.

4. In a boring machine, the combination of a shaft having a thread on its outer surface, a support, an element revolvably mounted in the support and having means to bear on the bottom of the thread of the shaft.

5. In a boring machine, the combination of a shaft having a thread on its outer surface, a support adapted to be shifted along the shaft, an element revolvably mounted in the support and having means to bear on the bottom of the thread of the shaft.

6. In a boring machine, the combination of a shaft having a portion adapted to bore a hole of relatively small diameter and a portion adapted to bore a hole of larger diameter, a thread on the outer surface of the shaft, the height of the said thread varying in accordance with the different bores to be made by the said portions, a support, an element revolvably mounted in the support, said element being constructed to have sliding movement relative to the shaft over substantially the full length thereof and having means to bear on the bottom of the thread.

7. In a boring machine, the combination of a shaft having a front portion adapted to bore a hole of relatively small diameter and a reamer adapted to bore a hole of larger diameter, a thread on the outer surface of the shaft and extending along substantially the full length of the shaft, the height of the thread varying in accordance with the different bores to be made by the front portion and the reamer respectively, a shiftable support, an element revolvably mounted in the support and having means to bear on the bottom of the thread, said element, reamer and thread behind the reamer being so constructed and arranged that the support and said element may be shifted along substantially the full length of the shaft.

8. In a boring machine, the combination of a shaft having a thread on its outer surface along substantially the full length thereof, cutting lips at the front end of the shaft and a reamer blade intermediate the ends, the height of the thread between the front end and the reamer blade being determined by the size of the cutting lips and the height of the thread behind the reamer blade being determined by the size of the reamer blades, part of the thread being cut away to form a lateral offset into which the cutting edge of the reamer blade projects, a shiftable support, an element revolvably mounted in the support, said element having a projecting portion bearing upon the bottom of the thread and contacting with the sides thereof.

9. In a boring machine, the combination of a shaft having a thread on its outer surface, a portion of the thread being cut away to define an off-set, a reamer mounted on

the thread so that its cutting edge projects into the said off-set, a support, an element revolvably mounted in the support, said element having a projection engaging in the 5 groove of the thread and bearing upon the bottom thereof.

10. In a boring machine, the combination of a shaft having a thread on its outer surface, part of the thread being cut away to 10 form a lateral offset, a reamer blade adjustably mounted in the thread and projecting into said offset.

11. In a boring machine, the combination of a shaft having a thread on its outer surface, part of the thread being cut away to 15 form a lateral offset, a reamer blade mounted

in the thread and projecting into the offset and means for adjustably securing the blade in the thread, said means comprising a wedge-shaped element positioned in a recess 20 in the thread and bearing on the blade and means for forcing the wedge-shaped element against the blade.

12. In a boring machine, the combination of a shaft having a multiple thread on its outer surface, part of the thread being cut away to 25 form lateral offsets and a reamer blade mounted in each thread and projecting into the offset.

In testimony whereof, I affix my signature. 30

HARRY S. STRONACH.
